UNITED STATES PATENT OFFICE.

ANDREW SIGFRID GUSTAFSON, OF CHATTANOOGA, TENNESSEE.

CAR-WHEEL.

No. 858,082.

Specification of Letters Patent.

Patented May 7, 1907.

Application filed January 12, 1906. Serial No. 226,787.

To all whom it may concern:

Be it known that I, ANDREW SIGFRID GUSTAFSON, a citizen of the United States, residing at Chattanooga, in the county of Hamilton and State of Tennessee, have invented a new and useful Car-Wheel, of which the following is a specification.

This invention relates to car wheels; and it has among its objects to provide a wheel which may be used upon all kinds of railroad cars and tram cars; and which shall be especially serviceable for and adapted to be used in connection with such cars as are used upon the trainways in mines, and similar localities, which shall be self lubricating, and which shall be simple in construction and efficient in operation; said invention being equally applicable to wheels constructed with or without spokes, such as plate and web wheels.

Other parts of the invention relate to improved means for excluding dust from the bearings; and for mounting or securing the wheels upon the axles.

With these and other ends in view, which will readily appear as the nature of the invention is better understood, the same consists in the improved construction and novel arrangement and combination of parts, which will be hereinafter fully described and particularly pointed out in the claims.

In the accompanying drawings has been illustrated a simple and preferred form of the invention; and in said drawings, Figure 1 is a side elevation showing the outer side of a car wheel constructed in accordance with the principles of the invention. Fig. 2 is a side view illustrating the inner side of the wheel. Fig. 3 is a vertical longitudinal sectional view. Fig. 4 is a vertical transverse sectional view taken on the plane indicated by the line 4—4 in Fig. 1. Fig. 5 is a sectional view, enlarged, of the plug or stopper valve for the oil reservoir. Fig. 6 is a sectional detail view, enlarged, taken on the plane indicated by the line 6—6 in Fig. 4.

Corresponding parts in the several figures are indicated throughout by similar characters of reference.

The improved wheel of the present invention is formed with a flange 1, rim 2, spokes 3, 3, hub 4, and with a housing 5; the latter forming or constituting an annular casing surrounding the hub; said housing being extended to form a bulging or conical closure for the outer end of the hub. The spokes, or

the webs constituting the spokes, are extended between the hub and the annular wall of the housing 5; but the outer wall, 6, of said housing is spaced from the spokes and from the outer end of the hub, thus forming a chamber or compartment 7 which directly communicates with each and all of the spaces or compartments 8, 8, which are bounded by the hub, the spokes, and the annular wall of the housing 5. A lubricant receptacle of large capacity is thus formed within the housing, and said receptacle is in direct communication with the outer end of the hub.

For the purpose of enabling lubricant to be supplied to the receptacle, valve plugs are used, two such plugs being shown in the drawings, although it is to be understood that one or more plugs may be used, as preferred. The wheel is provided with bores or recesses 9 forming seats for the plugs, which latter include tubular casings 10 provided near their outer ends with threads 11 engaging threads 12 at the outer ends of the bores. The casings 10 are provided at their outer ends with seats 13 for the valve plugs 14 which are forced in the direction of said seats by means of springs, as 15. The bores 9 communicate with the lubricant receptacle through passages, as 16, and the outer ends 85 of said passages are in alignment with ports 17 in the sides of the tubular casings, said ports being closed by the valve plugs 14 when the latter are seated. Said valve plugs thus serve a two-fold purpose in forming closures, 90 not only for the ports or seats 13, but for the ports 17 as well, thus making leakage practically impossible, or reducing danger thereof to a minimum.

To supply lubricant to the reservoir in the wheel, the valve plug is simply pushed back against the tension of the spring 15 by the spout of a force feed oiler, which latter is inserted into the port 17; when the oiler is withdrawn, the spring 15 automatically shuts the valve plug.

The inner end of the hub 4 is provided with an undercut groove 18; and the axle boxes 19 are provided with corresponding flanges 20, which engage said groove and thereby serve in a measure to secure the wheel upon the axle, which latter is shown at 21; the flange 20 of the lower axle box also serves as a receptacle for such lubricant as may escape at the outer end of the hub, between the hub and the axle, thereby preventing waste and keeping the axle boxes properly lubricated.

From the foregoing description, taken in connection with the drawings hereto annexed, the operation and advantages of this invention will be readily understood by those skilled in the art to which it appertains. The construction of the wheel is such that the lubricant compartment entirely surrounds and communicates with the outer end of the hub and with the extremity of the spindle upon which the hub is mounted, thus preventing the escape of lubricant from said compartment except by traversing the entire length of the spindle or axle journal. The construction is simple and inexpensive, and the device is thoroughly efficient for the purposes for which it is provided.

Having thus described the invention, what is claimed is:—

A car wheel formed in a single piece comprising a hub, a rim, spokes connecting the hub and rim, a housing interposed between the spokes and concentric with the hub, said housing extending over and inclosing one end of the hub to form a distributing compartment, there being a plurality of compartments formed between the spokes, hub and

housing, all of said compartments communicating at one end with the distributing compartment, one of the spokes being enlarged adjacent the housing and having a recess therein internally screw threaded, there being a passage from said recess and through the hub for discharging lubricant into the distributing compartment; and an externally screw threaded casing seated within the recess and having a contracted end constituting a valve seat, a tubular valve plug slidably mounted within said casing, and a spring within said plug and bearing thereagainst and against the inner wall of the recess for holding the plug normally upon its seat, there being an opening in the casing registering with the passage and normally closed by the valve plug.

In testimony that I claim the foregoing as my own, I have hereto affixed my signature in the presence of two witnesses.

ANDREW SIGFRID GUSTAFSON.
